TREATMENT OF PITCH

Frank J. Fontana, Long Beach, Calif., assignor to
Richfield Oil Corporation, Los Angeles, Calif.,
a corporation of Delaware

Application March 10, 1951, Serial No. 214,909

2 Claims. (Cl. 18—47.2)

1

My invention relates to the water quenching of hot molten petroleum pitch to produce a solid pitch conveniently adapted to conventional methods of storage and transportation. My invention is useful in the disposal of waste pitch produced in the conversion of heavy petroleum oils. More particularly, my invention finds special utility in the pitching process, described in the applications for United States Patents, Serial Nos. 136,069 and 135,427, now Patent No. 2,633,449; filed on December 28, 1949, by Harry L. Pelzer and by Leroy K. Cheney, respectively, by providing a means for converting the pitch produced therein to a form compatible with commercial handling methods whereby the pitch may be transported to a point of use or storage.

The current production of heavy petroleum residual products vastly exceeds the natural demand for such residua in any form. The before noted copending applications describe a process of pitching which increases the recovery of more desirable hydrocarbons from such residua, but which is, itself, accompanied by a large production of petroleum pitch. The problem of the disposal of such pitch is enhanced by almost complete lack of utility as such in quantity, since it is obtained in the liquid state at temperatures usually in excess of 500° or 600° F. and ranging upwards to 900° F. or more. Moreover, petroleum pitch has a softening point (R. & B.) which is of the order of 200° to 400° F. and, consequently, cannot be conveniently transported by pipe lines of any extended length without heavy insulation and expensive reheating requirements in order to maintain it in fluid condition. In addition, liquid pitch cannot be kept at temperatures necessary to maintain it in the liquid state for excessive lengths of time, as it is subject to coking and tar separation whereby the pipe lines and other vessels carrying such liquid pitch become plugged. As a consequence of these considerations, any means for solidifying the pitch, of necessity, must be located in the proximity of the pitching unit. Furthermore, the high softening point of the material prohibits conventional tank storage.

It has seemed necessary to dump the liquid pitch at some convenient location such as in a lake or on an open field. But, as the material cannot be dumped at one location continuously for any extended period of time, unless unlimited space is available, such procedure provides only a temporary solution. Ultimately, a new location must be found or the solid mass of pitch must be removed by blasting or other equally impractical

2

means. Since extended pipe lines are not commercially feasible, eventually the pitching unit must be closed down for lack of space in which to dump pitch.

5 The desirable solution of the problem is obviously a means by which hot liquid pitch may be cooled, solidified and fragmented so that it may easily be handled by conventional conveyors, elevators and other methods of transportation. It is even more desirable that the fragmented pitch should have some utility of itself, for example, as a fuel. It is to these ends that my invention is specifically directed.

By reason of the quantities of pitch which must 15 be handled by any practical cooling means adaptable to commercial operation, water appears to be the most feasible coolant from an economic standpoint.

I have found that hot liquid pitch can be economically and practically quenched with water on a commercial scale by pouring pre-cooled liquid pitch onto the surface of a body of water and forcibly submerging the blanket of pitch formed on the surface as soon as it forms.

20 25 Several previous proposals have been made using water as a coolant.

It has been proposed to use a water-cooled drum flaking unit to produce a flaked solid pitch. Such a method is satisfactory in small scale operation, but is not practical when normal commercial production is contemplated, as equipment costs and size become prohibitive. For example, for such a unit to handle 10 barrels of fluid pitch per hour, a relatively small quantity in a commercial sense, would require a pair of drums 10 feet by 10 feet. Moreover, vast amounts of power are consumed in rotating the drums against the flaking edge in order to overcome the strong adhesion of the solid pitch to the drums.

30 35 It has been proposed to effect cooling by water sprays directed against liquid pitch on a flexible steel conveyor belt. To operate such a system satisfactorily, even at the low pitch rate of 10 barrels per hour, would require a flexible steel belt conveyor of 120 inches' width. The largest such unit which appears to be available at this time is only 72 inches wide. Again, the equipment size for commercial operation is excessive.

40 45 50 It has before been proposed to cool liquid pitch by direct contact with a body of water. Such methods to this time have been unsatisfactory because the product is friable, bulky with low apparent density, and has a multitude of pores. Also, there is a large production of fines. Such

solid fragments as are produced quickly crumble when handled by conventional equipment such as conveyors and elevators. The fine particles are extremely difficult to dry and tend to clog standard mechanical handling equipment.

Moreover, hot fluid pitch is lighter than water and floats upon the surface forming a blanket. The underside of the blanket, which is in immediate contact with the water, as it cools and solidifies, becomes a thin, tenacious, rubber-like, flexible sheet which is an inefficient conductor of heat. The molten pitch above builds up and tends to spread over the surface of the water. Such heat as is transmitted through the blanket to the water generates steam which bubbles up through the molten pitch causing it to froth. Ultimately, the pitch solidifies in a sponge-like mass.

It is indeed surprising in view of these considerations to find that pitch may be quenched by direct contact with the water, yet I have found it possible to do so without excessive equipment cost or size. Moreover, the pitch produced when using my method and apparatus has substantially even fragment size, high density, and is non-friable. The fragments formed are smooth, hard and glassy-like from about 8-mesh size to 2" in size. They are particularly useful as a solid bituminous fuel, are easily dried and do not crumble when subjected to the rough handling of a screw conveyor.

I have been able to obtain such satisfactory results by pouring liquid pitch onto the surface of a body of water, by confining the blanket of pitch formed within a small area of such surface and by forcibly submerging the blanket beneath the surface as soon as it is formed.

It is also essential to the production of hard, fragmented pitch, as described above, that, prior to pouring the hot liquid pitch onto the surface of the water, it be cooled to a temperature between the softening point temperature of the pitch and the temperature at which the density of the liquid pitch is equal to that of the coolant water. Failure so to pre-cool the hot liquid pitch results in a soft, porous product, produces a less even fragment size and causes a large production of fines and floaters.

The drawings illustrate an apparatus which is specifically adapted to carrying out the process of my invention and which is itself part of my invention.

Figures 1, 2 and 3 show the entire apparatus, respectively, in elevation, plan and cross-sectional views. The cross-sectional view in Figure 3 is taken from line 3—3 in Figure 1.

Figures 4, 5 and 6, are, respectively, elevation, plan and cross-sectional views of a particular portion of the same apparatus, enlarged to show the important details. Figure 6 is taken at line 6—6 of Figure 4.

The reference numeral 1 designates a tank adapted to confine a body of water, open at its top and tapered inwardly and upwardly at one end. Thus bottom 2 of tank 1 inclines upwardly toward the tapered end. A launder 3 is provided to maintain the level of water surface 4 in tank 1.

At a central point of the water surface 4, cross planks 5 and 6 and longitudinal planks 7 and 8 are positioned to form an open-ended box which confines a small portion of water surface 4. The planks 5, 6, 7 and 8 are positioned to extend a short distance above and below the level of water surface 4.

An inclined catch pan 9 is mounted above the

tank in a position to direct the pitch poured thereon to fall into the center of the area of surface 4 enclosed by the box formed of planks 5, 6, 7 and 8. Catch pan 9 is conveniently provided with sides 10 and 11, and its lower edge is advantageously provided with an upwardly inclined serrated weir 12.

A continuous chain belt 13 is mounted on wheel and axle assemblies 14, 15 and 16 which are mounted to the sides of tank 1.

The belt 13 comprises two continuous chains 17 and 18, which advantageously are of roller chain construction and which are adapted to pass over wheels 19, 20 and 21 of assemblies 14, 15 and 16, respectively. Wheels 19, 20 and 21 advantageously are of the sprocket type adapted to receive the links of chains 17 and 18. Cross bar 22 with drag bars 23 mounted thereon are spaced at intervals between chains 17 and 18. Chain belt 13 is conveniently driven by a motor 24 mounted at one of the wheel and axle assemblies, for example, the assembly 16 as shown in Figures 1 and 2.

Chain 13 is so positioned by assemblies 14, 15 and 16 that it passes downwardly through the area of surface 4 confined by planks 5, 6, 7 and 8 to wheel and axle assembly 14 located at the lower end of bottom 2 within tank 1. Chain 13 then passes upwardly along inclined bottom 2 to wheel and axle assembly 16 located at the outer tip of the tapered end of tank 1. From assembly 16, chain 13 nearly reverses the direction of its path to return above tank 1 to assembly 15 and thereby complete its path. Chain guards 27 are provided intermediate assemblies 14 and 15 to prevent the formation of pitch on chains 17 and 18 as chain belt 13 passes downwardly into tank 1.

Conveniently, tank 1 is provided with a hopper 25 mounted as a continuation of bottom 2 directly beneath assembly 16. Solid pitch dragged by chain belt 13 from the bottom of tank 1 is thereby discharged into hopper 25 where it may be collected. Hopper 25 conventionally may be adapted to discharge onto a continuous conveyor 26, for example, for transfer to a zone of storage, use or disposal.

In carrying out my process, hot molten pitch, which typically is withdrawn from a pitching unit such as is described in the before noted copending applications of Harry L. Pelzer and Leroy K. Cheney, is first subjected to a pre-cooling operation.

Pre-cooling may be effected by several means. It is preferred that the step be carried out in a conventional shell and tube heat exchanger using high pressure steam or hot oil as the coolant. It is, however, practicable to cool the pitch in a drop stack using air, steam or a water fog as a direct contact coolant. The drop stack method is considered less desirable, primarily as it does not provide a good temperature control. Temperature control in the pre-cooling operation is quite critical as the pitch must not be cooled so close to its softening point that it may clog the equipment used to distribute it onto the water surface.

If a heat exchanger is employed, as in the preferred form, almost any coolant, consistent with the economics involved, will be satisfactory if it is capable of being maintained at a temperature above the softening point of the pitch. Water is not satisfactory. The temperature of cooling water without pressure is too low so that a film of pitch solidifies on the inner surface of the tubes, thereby resulting in poor heat transfer and

eventual clogging of the tubes. High pressure steam may be used but advantageously fresh feed to the pitching unit is employed. The pitcher feed will normally arrive at the unit hot or will receive preheat by exchange in the usual manner prior to the exchange with the hot pitch. Also, additional preheat is provided for the feed, assisting the thermal balance of the unit.

The hot liquid pitch, at the temperatures at which it is withdrawn from the pitching unit, has a density which is less than that of the water in the quench tank. However, as liquid pitch is cooled, its density increases, and equals and then exceeds that of water before the pitch hardens.

The table illustrates the relationship between specific gravity and temperature of two pitches which are typical.

Temperatures, ° F.	Specific Gravity A	Specific Gravity B
705		0.97
640	0.99	1.02
555		1.05
500	1.02	
470	1.05	
400		1.18
81	1.12	
77		

"A" is a pitch with an R. and B. melting point of 282° F.
"B" is a pitch with an R. and B. melting point of 354° F.

Such pitches are drawn from a pitching unit at typical temperatures of about 550° F. to 650° F. According to my invention the hot pitch is pre-cooled to about 400° F. in the case of pitch A or about 450° F. in the case of pitch B at which temperatures the pitch has a specific gravity greater than that of water, but is in a free and running condition and not thick and viscous as it would be at temperatures closer to the softening point.

The pre-cooled pitch is delivered without substantial temperature loss to the apparatus pictured in the drawings where it is poured onto catch pan 9, for example, through a nozzle. Catch pan 9 is suitably warmed prior to the initiation of operation to prevent its clogging during warm-up. Chain belt 13 is moving in a counter-clockwise manner as illustrated in the drawings and water is placed in the tank to the level indicated so that planks 5, 6, 7 and 8 extend above and below the level of water surface 4 to a depth sufficient to confine the floating blanket of pitch.

As the liquid pitch falls off catch pan 9 into the open-ended box formed by planks 5, 6, 7 and 8 it is somewhat broken up and separated by serrated weir 12. Drag bars 23 which are continuously passing downwardly through the box pull the pitch under water surface 4. Any blanket of pitch forming on water surface 4 is confined between planks 5, 6, 7 and 8 and so is readily submerged by drag bars 23.

Once under water the pitch solidifies in fragments and sinks to the bottom of tank 1.

As the size of tank 1 is necessarily limited, cold water make-up must be added continuously or intermittently to prevent excessive rise of temperature in the water in tank 1. The temperature of such water is not critical except that

of course the cooler the water, the quicker the pitch solidifies. I have found it quite practical to maintain a water temperature in the range of about 110° F. or less. However, higher temperatures may be employed. A great part of the heat removed from the pitch is absorbed by the generation of steam from the water in immediate contact with the molten pitch with the result that the control of the average temperature of water in tank 1 is not difficult.

I have found it quite convenient to add make-up cold water by spraying it on chain belt 13, particularly on cross bars 22 and drag bars 23 just prior to their entry into the box formed by planks 5, 6, 7 and 8. Such point of addition serves a second useful result inasmuch as liquid pitch exhibits a minimum adhesive effect to wet metal. It is not quite as convenient to add make-up water by wetting the surface of catch pan 9 as such practice may cause excessive cooling of catch pan 9 and result in the partial solidification of pitch thereon with the eventual clogging of catch pan 9 and interruption of operation. The solidified pitch fragments sink to the bottom 2 of tank 1 where they are removed by the chain belt 13 as it moves upwardly across bottom 2, and are discharged into hopper 25, from which they may conveniently be removed on conveyor 26.

A possible alternative process would involve the removal of catch pan 9 and introduction of pre-cooled liquid pitch directly into the area of water surface 4 enclosed between open-ended box formed by planks 5, 6, 7 and 8. However, I prefer the means illustrated by the apparatus shown in the drawings.

I claim:

1. In the process of cooling and solidifying hot molten petroleum pitch by contact with a water coolant, the steps of pouring hot molten pitch, at a temperature above the softening point temperature of the pitch but below the temperature at which the specific gravity of the pitch is less than that of the water coolant, onto a surface of a body of water coolant, and mechanically pulling the pitch beneath the said surface of the body of water.

2. In the process of cooling and solidifying hot molten petroleum pitch by contact with a water coolant, the steps of cooling the hot molten pitch to a temperature above the softening point temperature of the pitch but below the temperature at which the specific gravity of the pitch is less than that of the water coolant, pouring the cooled liquid pitch onto a surface of a body of water coolant, and mechanically pulling the pitch beneath the said surface of the body of water.
